UNITED STATES PATENT OFFICE.

BENNET HOTCHKISS, OF NEW HAVEN, CONNECTICUT.

IMPROVEMENT IN TRIP-HAMMERS.

Specification forming part of Letters Patent No. 42,581, dated May 5, 1864.

To all whom it may concern:

Be it known that I, BENNET HOTCHKISS, of New Haven, in the county of New Haven and State of Connecticut, have invented new and useful Improvements in Trip-Hammers; and I do hereby declare the following to be a full, clear, and exact description of the construction and operation of the same, when taken in connection with the accompanying drawings and the letters of reference marked thereon, and which said drawings constitute part of this specification, and represent, in—

Figure 1, a front elevation; Fig. 2, a side view, and in Fig. 3 a vertical section of the cylinder.

Similar letters of reference indicate like parts.

My invention relates to hammers operated by means of a cylinder, and particularly to hammers for which Letters Patent were granted to me on the 14th day of June, A. D. 1859, and the 15th day of September, A. D. 1863; and it consists in arresting the hammer at its highest point of ascent, or at any point during its descent, for the purpose of adding force to the blow to be given, by compressing the air within the cylinder or other spring to act upon the hammer, thereby increasing the force of the blow by so much as the power of the spring, or of the portion of its power employed, the object being to reduce the weight of the hammer for a blow of a given force, as also to afford a greater range of force with the same hammer.

To enable others skilled in the art to make and use my improved hammer, I will proceed to describe its construction and operation.

A is the bed, on which rests an anvil, B. C C are vertical guides, between which, and moving freely up and down, is fixed the cylinder D, the lower part of which forms the hammer. E is a piston within the cylinder D, and fixed to or made a part of the piston-rod F. G is a cross-head running on the guides C C, and to which the piston is attached. H is the driving-shaft, to the inner end of which is fixed the crank I, and connected by the rod K to the cross-head G. Through the cylinder, and about midway of the stroke of the piston, I make an aperture, a.

When power is applied to the driving-shaft, and the piston thereby made to traverse within the cylinder, the piston will rise to and pass the

aperture a and compress the air within the cylinder above the aperture and between the piston and cylinder-head until the compression overcomes the weight of the hammer. Then the hammer will be taken up the remainder of the stroke. A rapid velocity, together with the elasticity of the compressed air, gives to the ascending hammer a momentum which carries the hammer more or less above the full stroke of the crank. In descending, the piston in advance of the cylinder, in consequence of the momentum, as aforesaid, repasses the aperture a and compresses the air in the lower part of the cylinder, to add the force of such compression to the natural force of the falling hammer.

Thus far the construction is substantially the same as described in the Letters Patent aforesaid. To add still more to the force of the blow, I attach to one of the guides a latch-lever, L, and make a notch, b, in the cylinder or hammer. As the cylinder rises, this said notch will catch upon the latch c, and there remain until the piston descends and compresses the air in the lower part of the cylinder, and the cross-head strikes the projections d in the lever L, which forces the latch from the notch in the cylinder or hammer. When thus released, the hammer descends with a velocity in proportion as the air in the cylinder is more or less compressed. Without other mechanical contrivance the force would be the same at all times, (the velocity being the same.) To regulate the force I employ means substantially the same as described in my application for a patent which was issued September 15, 1863. I insert in the side of the cylinder, and near the bottom, a puppet or other valve, e, (see Fig. 3,) its stem f projecting from the cylinder, and the valve opening inward. On the guide I place an adjuster, M. This adjuster is drawn down by a spring-treadle, N, and placed so that when drawn down it will strike the stem of and open the valve e. If the full force of the compression allowed by the latch is not required, I press upon the treadle to draw down the adjuster. This forces in and opens the valve e to allow a portion of the air to escape, the operator being the judge of the quantity required to give the desired blow. By this arrangement the force of the blow is at the entire command of the operator.

I have described the spring to be used as of the atmosphere; but any other spring may be

substituted therefor, and in lieu of allowing a part of the air to escape the latch may be released sooner or later, and the hammer allowed to descend accordingly as the blow required is less or greater. Therefore, without confining myself to an atmospheric cylinder, and having fully set forth my invention,

What I claim as a new and useful, and desire to secure by Letters Patent, is—

Arresting the stroke of the hammer by means

of the latch L or its equivalent, when the said latch is arranged in combination with the hammer and cross-head to operate automatically in the manner for the purpose substantially as described.

BENNET HOTCHKISS.
